UNITED STATES PATENT OFFICE.

JOHN McGAW, JR., OF KINCARDINE, ONTARIO, CANADA.

SHIPPING APPARATUS FOR GILL-NETS.

1,051,610.

Specification of Letters Patent. Patented Jan. 28, 1913.

Application filed May 19, 1911. Serial No. 628,327.

To all whom it may concern:

Be it known that I, JOHN McGAW, Jr., of the town of Kincardine, in the county of Bruce, in the Province of Ontario, Canada, 5 have invented certain new and useful Improvements in Shipping Apparatus for Gill-Nets, of which the following is the specification.

My invention relates to improvements in 10 shipping apparatus for gill nets, and the object of the invention is to provide a simple apparatus whereby a net may be readily drawn aboard ship with a minimum amount of labor and such an apparatus as may be 15 readily used to ship the nets either from one side of the boat or the other and it consists essentially of a rotatable horizontally disposed drum like member having stationary lower and vertically movable upper jaws 20 designed to successively close to grip the lines of the net as the apparatus revolves, so as to draw the net inboard as hereinafter more particularly explained.

Figure 1, is a vertical elevation partially 25 in section of my device. Fig. 2, is a plan view of my device. Fig. 3, is a vertical section on line $x-y$ Fig. 2. Fig. 4 is an enlarged perspective detail showing the brackets and gripping jaws of the device. 30 Fig. 5 is an enlarged elevation with part in section of the brackets and gripping jaws shown in detail.

In the drawings like letters of reference 35 indicate corresponding parts in each figure. A is a portion of the ship's deck and B is the gunwale.

C is a vertical supporting stud provided 40 with a suitable base C¹ secured to the deck A. The stud C is provided with a reduced upper end C¹ and a further reduced sided portion C² extending upwardly from the portion C¹.

D is the base plate of the apparatus provided 45 with a central hub D¹ through which extends the portion C¹ of the stud shaft C. The base of the hub D¹ rests upon the shoulder C³ formed between the reduced portion C¹ and the main portion C.

E are a series of brackets secured to the 50 base plate D and arranged around the edge and spaced equi-distant apart and having V-shaped vertical guiding grooves E¹ at each side thereof. The brackets E are formed with flanges L which rest upon and 55 are bolted or otherwise suitably secured to

and flush with the outer edge of the base plate D.

F are stationary jaws secured to the base plate D between each pair of brackets E.

F¹ are movable jaws provided with V-shaped tongues F² fitting within the V-shaped grooves E¹.

F³ are stems depending from the movable jaws F¹ through the openings F⁴ in the stationary jaws and holes F⁵ in the base 65 plate D. The lower ends of the stems F³ are threaded and provided with suitable nuts and washers F⁶.

F⁷ are compression springs extending between the nuts and washer F⁶ and the lower 70 base plate D.

F⁸ are pins extending inwardly from the movable jaws F¹ and F² are rollers journaled upon the pins F⁸.

G is a hub having a central opening G¹ 75 having a circular portion G² and a sided portion G³. The circular portion of the center opening of the hub G fits the reduced portion C⁴ of the stud C.

H is a washer provided with a sided central boss H¹ fitting the sided portion G³ of the central opening of the hub G and having a sided central opening H² fitting the sided portion C² of the stud C. 80

I is a cam ring connected by spokes I¹ to 85 the hub G and having a segmental opening I². The cam ring I is provided with a gradually inclined portion extending from the side 2 of the opening I² to the point 3 and a steep inclined portion extending from the side 4 to the point 5. It will be understood 90 that the cam ring fits to the inside of the brackets E and the stationary and movable jaws F and F¹ respectively and that the rollers F⁹ successively come into engagement with the gradually inclined portion of the cam ring I. The hub D¹ of the base D is provided with a face gear D² meshing with the pinion D³ mounted upon a suitable driving shaft D⁴. By this means my apparatus 95

is rotated.

D¹ is provided with a face gear D² meshing with the pinion D³ mounted upon a suitable driving shaft D⁴. By this means my apparatus 100

K is a roller journaled in brackets K¹ secured to the part outside of the gunwale of the boat. The brackets K¹ are provided with T-arms K² extending to the periphery 105 of the roller K for a purpose which will hereinafter appear.

J is an annular trough extending around my apparatus and provided at its upper side with a platform J¹ extending in prox. 110

imity to the roller K and a delivery spout J² having a suitable receptacle.

Having described the principal parts involved in my invention I shall briefly describe the operation of the same.

The ends of the lines of the gill net are drawn up so as to enter between the opening jaws. The driving shaft D⁴ is then thrown into engagement so as to rotate my apparatus. As it revolves the rollers F⁹ pass onto the stationary inclined portion extending from 4 to 5 down which they are carried by the tension of the springs F⁷, thereby carrying the movable jaw into engagement with the stationary jaw, so as to grip the lines of the gill net therebetween. As the apparatus continues to revolve the rollers pass the opening in the cam ring I extending between the points 4 and 2 during which time they are held closed. The rollers then successively engage with the gradually inclined portion of the cam ring I extending from the point 2 to the point 3. The rollers F⁹ gradually ascend the inclined portion, thereby moving the movable jaws against the compression of the springs F⁷, thereby again opening the jaw and releasing the lines. The net is gradually drawn over the rollers K with the fish thereon and fed through the spout J² into a suitable receptacle. The arms K² serve to guide the net in proper alignment on the roller K, so that the lines will always enter between the stationary and movable jaws F and F¹ respectively.

When it is desired to ship a net from the opposite side of the boat all that it is necessary to do is to remove my apparatus to the required side. I then release the cam ring I by lifting off the washer H and the hub G. The cam ring may then be reversed so as to operate the movable jaws in a similar way to that previously described and as the apparatus rotates in the opposite direction feed the net inboard on the opposite side of the boat.

What I claim as my invention is:

1. An apparatus for drawing gill nets inboard comprising a circular suitably supported rotatable base plate, a series of stationary jaws secured at the edge of the base

plate in proximity to the periphery thereof and suitably spaced apart, brackets located between each pair of jaws and having vertical guiding grooves, movable jaws located above the stationary jaws and having tongues fitting the guiding grooves of the brackets, spring means for normally holding the stationary and movable jaws together, so as to successively grip the lines of the net, and means for successively separating the stationary and movable jaws apart so as to free the lines of the net, as and for the purpose specified.

2. An apparatus for drawing gill nets inboard comprising a gripping member provided with a series of stationary gripping jaws and intervening vertical guide-ways, movable jaws located above the stationary jaws and between the guide-ways, stems extending from the movable jaws and through the stationary jaws having suitable enlargements at their lower ends, and compression springs interposed between such enlargements and the stationary jaws and means for successively opening the jaws against the pressure of the aforesaid springs, so as to successively free the lines of the net, as and for the purpose specified.

3. An apparatus for drawing gill nets inboard comprising a central stud having a reduced upper portion and rotatable member supported thereby having peripheral stationary and movable jaws arranged around the same, projections extending inwardly from the movable jaws, a face cam ring coacting therewith having a central hub having a sided central opening having a cylindrical lower portion designed to fit the aforesaid supporting stud and extend around the sided extension of the supporting stud, and a washer having a sided boss designed to fit within the sided portion of the opening of the hub and having a sided central opening designed to fit the sided extension of the supporting stud, as and for the purpose specified.

JOHN McGAW, JR.
